UNITED STATES PATENT OFFICE.

HUGO PRAHL, OF DUSSELDORF, GERMANY, ASSIGNOR TO RHEINISCHE METALL-WAAREN- UND MASCHINENFABRIK, OF DUSSELDORF-DERENDOF, GERMANY, A CORPORATION OF GERMANY.

COMBINED TIME AND PERCUSSION FUSE.

1,144,242.

Specification of Letters Patent. Patented June 22, 1915.

Application filed February 17, 1915. Serial No. 8,862.

To all whom it may concern:

Be it known that I, HUGO PRAHL, engineer, a subject of the German Emperor, residing at 79 Uerdingerstrasse, Dusseldorf, Germany, have invented certain new and useful Improvements in Combined Time and Percussion Fuses; and I do hereby declare the following to be a full, clear, and exact description of the invention, such as will enable others skilled in the art to which it appertains to make and use the same.

My invention relates to improvements in combined time and percussion fuses of the kind in which the detent of the firing pin is effected by unlocking a rocking arm by means of the time or by means of the percussion device. According to my invention I arrange on this rocking arm a double armed lever abutting with one of its arms against a bolt rotated by means of the time fusing device and with its other arm against a bolt protruding during the impact of the projectile so that the lever steps aside and releases the rocking arm if the bolt influenced by the time fusing device is turned and also if the other bolt protrudes during the impact. By the arrangement in the said double armed lever the conditions of friction are more favorable than if the detent arm is locked directly by both bolts influenced by the time fusing device and by the impact respectively.

An embodiment of my invention is shown in the accompanying drawing in which—

Figure 1 is a longitudinal section and Fig. 2 a cross section through the combined fuse.

In the represented combined fuse there is for time and impact action only one primer bolt *g* pressed by a spring *p* with an inclined surface *d* against a correspondingly inclined projection *c* of the fuse frame. In consequence of this arrangement the primer bolt *g* is adapted when unlocked to turn under the influence of the inclined faces pressed together; and by such rotation the recess *z* of the bolt (Fig. 2) is brought under the projection *c* whereupon the primer bolt *g* with its primer is thrown against the needle *e*.

In its normal position the primer bolt *g* is prevented from being turned by the following arrangement. On the primer bolt *g* a rock arm *i* is fastened and provided with a small double armed lever *l* pivotally mounted on the rock arm *i*, one arm of the said double armed lever *l* abutting against a flattened portion of a bolt *j* and the other arm abutting against a bolt *o*. The bolt *j* is connected in any well known manner with a time fusing device of any known construction in such a manner, that the flattened portion of the bolt *j* is turned away from the lever *l* sometime after firing, the said time being adjusted in an ordinary way by the timing device. As soon as the flattened portion of the bolt *j* releases the small lever *l* the rock arm *i* is free to be turned by the spring *p* and the inclined surfaces of *d* and *c* so that the primer bolt *g* is thrown against the needle *e* in the aforesaid manner.

If the shell is to be exploded by impact the bolt *o* protrudes in the moment of impact whereby the abutting arm of the lever *l* is freed so that the rock lever *i* is again rotated under the influence of the spring *p* and of the inclined surfaces. The primer is then thrown by the spring *p* against the needle.

Having thus described my invention what I claim is:

In a combined mechanical time and percussion fuse the combination of a rock arm connected with the priming device; a double armed lever pivoted on the rock arm, a bolt operatively connected with the time fusing device and a second bolt adapted to protrude on the impact of the shell, the said lever abutting with its both arms against the said bolts respectively.

In testimony whereof, I have signed this specification in the presence of two subscribing witnesses.

HUGO PRAHL. [L.S.]
